(57) **CLAIM**

The ornamental design for a diagnostic analyzer, as shown and described.

DESCRIPTION

FIG. 1 is a front perspective view of a diagnostic analyzer, showing our new design;

FIG. 2 is a front view thereof;

FIG. 3 is a rear view thereof;

FIG. 4 is a right side view thereof;

FIG. 5 is a left side view thereof; and,

FIG. 6 is a top view thereof.

The bottom view of the diagnostic analyzer is not shown and forms no part of the claimed design. The broken lines in the drawing views are included for the purpose of illustrating portions of the diagnostic analyzer that form no part of the claimed design.

1 Claim, 6 Drawing Sheets
